UNITED STATES PATENT OFFICE.

HONESTUS M. ALBEE, OF NUTLEY, NEW JERSEY,

MACHINE FOR CARVING, ROUTING, AND SIMILAR OPERATIONS.

1,349,250.

Specification of Letters Patent. Patented Aug. 10, 1920.

Application filed April 16, 1919, Serial No. 290,410.

To all whom it may concern:

Be it known that I, HONESTUS M. ALBEE, a citizen of the United States, and a resident of Nutley, county of Essex, and State of New Jersey, have invented certain new and useful Improvements in Machines for Carving, Routing, and Similar Operations, of which the following is a specification.

This invention relates to an improved machine that can be used for carving and also for routing, being adapted for use on different materials, but is particularly adapted for engraving, routing or otherwise acting on the surface of wood.

The invention is designed to provide a machine of this kind in which a tracer tool and an operating tool are operated in unison as to direction and are adjustable, so that the reproduction and the pattern can be of the same size, or the reproduction can be made smaller or larger than the pattern, this difference in size applying in all directions.

The invention is further designed to provide a machine of this kind that is easily operated, but that is substantial enough to insure an accurate reproduction of the pattern, and is also adapted to be used for engraving and other purposes without the use of a pattern. To this end the invention consists of various combinations of coöperating elements which are hereinafter more fully described and are finally embodied in the clauses of the claim.

The invention is illustrated in the accompanying drawing, which shows one embodiment of the machine, in which drawing Figure 1 is a top view of the machine, Fig. 2 is a side view, Fig. 3 is a vertical section on line 3-3 in Fig. 2, Fig. 4 is an enlarged detail section of a hinge used in the machine, and Fig. 5 is a diagrammatic view to illustrate the character of the work to be accomplished by this machine. Fig. 6 is a detail view of a shaft for regulating the movement of the bars. Fig. 7 is a detail perspective view showing the end of a spring which holds the tool yieldingly in alignment, and the top end of a support on which the end of the spring rests.

The machine can be fastened to a suitable standard and can be in fixed position if desired, but I prefer to make it portable. I have not illustrated in the drawing any support other than the table 10 which acts as a support for the rest of the mechanism.

and is preferably provided with suitable work holding means, in the form shown this consisting of a slot 11 in which a strip 12 is placed with screw holes 13 spaced 60 therein so that the pattern or the work to be operated on can be screwed down and held in position, but it will be understood that other means can be employed for this purpose.

To secure lateral movement of the working elements, to be hereinafter described, I construct the machine with a main support or head that can be swung horizontally, and in the form shown a plate 14 is 70 mounted so that it can swing, and in order to minimize the friction I usually place the balls 15 so as to provide a ball bearing for the plate 14, the plate 14 thereby being adapted to be easily swung in a horizontal 75 plane, and, if desired, can be locked against swinging, one form of lock being shown and consisting of a block 16 having a latch 17 adapted to slide in the block and being actuated by a handle 18 setting in a notch 80 19 in the latch, the end of the latch being adapted to fit in various recesses 20 in the periphery of the plate 14.

On the plate 14 is a housing 21 which supports a pair of slidable arms 22 and 23, 85 these being adapted to be supported at various heights by suitable means, the means shown consisting of blocks 24 which are slightly set into the ends of the housing 21 to prevent their side movement, and being held in their adjusted position by the screws 25, which pass through the slots 26 and are secured in the housing 21. The arms 22 and 23 are slid able, one manner of sliding them being by means of pinions 95 27 and 28 which are in mesh with racks 29 and 30 on the rods 22 and 23, respectively, the pinions being secured to the shaft 31, which has suitable means for operating, such as a handle 32.

The shaft 31 is removable so that, if desired, different sizes of pinions can be placed on the shaft, within the housing, and in this way the movement of the arms is made proportionate to the ratio of the length of movement. In other words, the speed of movement of the arms relative to each other can be changed by the insertion of different sizes of pinions, and when one of said arms is moved, the other is moved whether said movement comes from a manipulation of the handle 32 to cause the pinions to

rotate, or whether it comes from a direct movement of either one of the arms.

The shaft, as has been stated, is removable, and I have found, in a machine now 5 in use, that this can be easily accomplished by making the dotted portion of the shaft 31 in Fig. 1 of a diameter so that it is a tight fit within the pinions 27 and 28, this tight fit being sufficient to hold the shaft 10 in its position when the machine is being operated, but it will be understood that other means for removably securing the shaft 31 in place can be employed.

Such direct control of the arms is provided for by means of the handles 33 which are placed on the rear ends of the arms and are usually pivoted, as at 34, so that the handles can be swung down out of the way if desired, or either one of them can be 20 moved up as shown in dotted outline in Fig. 2.

If it is desired for any reason to hold the arms 22 and 23 against movement, a suitable locking mechanism can engage either of the 25 arms to hold it in position, the locking means shown consisting of a set screw 35 which bears down on the arm 23 after passing through the block 36, which is shaped on its under face to engage the upper sides 30 of the arms to assist in guiding them, the set screw 35 being used only when it is desired to hold the arms against movement, since the block 36 is held in position by means such as a bolt 37.

Suitable tools, either in the way of tracer tools or operating tools, are carried by the arms, and to provide for their movement in as many directions as possible, they are preferably mounted so as to be movable to a 40 limited extent in a vertical direction, and to provide for this the arms 22 and 23 have the extensions 38 and 39, respectively, these extensions being hinged as at 40 and 41, the preferred form of hinge being shown in detail in Fig. 4, where the hinge 40 is shown consisting of a pair of disks or washers 42 in inwardly turned marginal flanges 43 which are set into the material of the two connected elements, such as the arm 22 and 50 the extension 38, these washers being held in position by a screw or bolt 44, a screw being preferable on account of providing for a smooth outside surface.

It will thus be seen that the whole strain 55 comes on the marginal flanges of the washers 42 and the pin has no strain except a longitudinal one, caused by holding the parts together laterally.

The upward movement of the hinge is 60 limited by the edges 45 abutting, the downward movement being limited by similar abutting edges of the adjacent elements that are hingedly connected, so that a substantially stiff extension is provided that is held 65 in alignment but is free to swing vertically.

The tracer tool and the operating tool are mounted in suitable devices, these devices being interchangeable, that is, either of the tools can be placed on the arm that projects most or the one that projects least from the head or support. In the form shown 70 the tracer tool 46 is shown in the outermost position, being mounted so that it is vertically adjustable in a device 47, being held in position by a set screw 48 passing through the body portion of the device 47, the tool holder or device 47 being slidable by reason of a dove-tailed slide 49 sliding in the groove 50 of the end 39, and being held in its various horizontally adjusted 75 positions by a suitable set screw 51, and the operating tool is mounted in a device or holder 52 which has an extension 53 that fits in a dove-tailed groove 54 in the end 38 and is held in adjusted position by a set screw 55. A spindle 56 is adapted to carry the operating tool 57 in a suitable chuck or by any other means, and is provided at its upper end with means for attaching it to a flexible shaft 58 and is also preferably provided with a momentum head 59 that insures 80 its steady operation.

To provide for the disengagement, if desired, of the operating tool from the work on which it is operating, the spindle 56 is 85 made vertically movable in its holding device 52 and is provided with a collar 60 which is connected by pins in the fork 61, which is pivoted at 62 to the frame 63 and has a handle 64 thereon so as to raise it up 100 by pressing on the handle. The downward movement of the spindle is limited by reason of having the fork 61 normally resting on a screw 65 which is provided with a nut 66 so that the screw can be raised or lowered, 105 the screw being locked by a lock nut 67 with a projecting handle 68 thereon.

To provide for the simultaneous upward movement of the tool holders or tool holding devices, I provide a yielding means 110 which, in the form shown, consists of a flat spring strip 69 which is held up on one end 70 by a strip 71 on the block 36, both the strip 69 and the strip 71 being notched, which notches are in engagement so that the 115 strip 69 cannot slide, the outer end of the strip 69 resting on a small pulley or wheel 72 which is fastened to the outermost holder 47 and the strip passes directly underneath a pulley or wheel 73 which is carried by the 120 holder 52. The pulleys 72 and 73 are grooved so as to receive the edge of the strip 69. If desired, the strip 69 can have scale 125 marks on it to indicate the distance from the center of the swinging support or head 14, and by which scale the tools can be adjusted from such center. The parts are disposed so that the center of swinging movement of the device and the centers of the tools are in line radially.

It will be evident that if the handle 32 is turned and the arms 22 and 23 are not locked against movement, these arms will be slid so as to project more or less from the head, and if the pinions operating these arms are of different sizes, their ratio will determine the ratio of movement of these arms.

If the machine is to be used manually, one of the handles 33 is swung out to the dotted position shown in Fig. 2, and the device is grasped much in the same way as a carpenter would grasp a jack plane, the handle 33 being grasped by the right hand, the tool end of the device being guided by the left hand, and by a back and forth movement or swinging movement, as desired, the tracer tool and the operating tool can be made to move in any desired direction, the ratio of their movement being defined by the ratio of the pinions 27 and 28 one to the other.

If a reproduction is to be made smaller than the pattern, the operating tool is put at the innermost position and the tracer tool at the outermost position, and if a reproduction is to be larger than the pattern, the tracer tool is put at the innermost position and the operating tool at the outermost position.

Another way of using the device is to fasten the pattern and the work in position and then operate the device from the tracer tool, guiding it in the desired direction, or in case a pattern of well defined outline is to be followed, simply placing this tracer tool on the pattern.

In Fig. 5 I illustrate a pattern 74, the tracer tool 46 being shown in various positions therein, and corresponding positions of the operating tool 57 are shown on the smaller reproduction 75 made thereby. Assuming that this is a groove that is to be routed in a piece of material, the tracer tool, following the groove in the pattern, causes a corresponding but smaller reproduction by the operating tool. The upward movement of the tracer tool causes a corresponding upward movement of the operating tool by reason of the strip 69 being raised when the tool holder 47 is raised, the strip 69 in turn raising the tool holder 52, these parts returning by gravity to their positions, this gravitation being assisted usually by the fact that the strip 69 is made of yielding or spring material. When it is desired to make straight parallel reproductions, the rotatable head can be placed in the proper position, locked by the latch 17, and then straight sliding movement of the arms 22 and 23 results in similar movement by the tracer tool and the operating tool.

In Fig. 6 I illustrate a means for regulating or controlling the feeding of the arms when such feeding should be very gradual, such, for instance, as when a very fine tool is traversing a fine piece of work, on each

traverse the tool is advanced but a very slight distance. One means of controlling this is illustrated in Fig. 6, in which the bracket 76 is mounted on a swinging element, such as the plate 77, which is pivoted at 78 and the device can thus be swung into and out of operative position. The bracket contains a shaft 76^a which has on the top thereof a hand piece 79 by means of which it can be turned, the hand piece being adapted to be held against accidental movement by suitable means, such as the strip 82, which has a slight projection, and the strip 82 being made of spring material, it snaps into the serrations or grooves in the edge of the hand piece 79 and holds the hand piece against accidental movement. When, however, the tool is to be advanced, the hand piece 79 is turned and the worm 81 on the shaft 76 engages the worm gear 80, which is provided on the edge of the wheel 32, and a very slight advance of the bar carrying the tool is thus provided for.

Other means of insuring such gradual advancement can be provided, so long as it makes it unnecessary for the operator to attend to the tedious slight advance for each time the tool traverses the work laterally.

I claim:

1. A machine of the kind described comprising a rotatable head, arms freely slidable on the head, means connecting the arms to control their movement relative to each other, and means on the arms for holding tools.

2. A machine of the kind described comprising a rotatable head, arms freely movable horizontally on the head but arranged to swing therewith, and means for moving the arms at various ratios.

3. A machine of the kind described comprising a rotatable head, arms sliding freely on the head and projecting therefrom, means for securing each arm in various fixed positions relative to the other arm, and means on the arms for supporting the required tools.

4. A machine of the kind described comprising a rotatable head, arms sliding freely on the head and projecting therefrom, and a single means for moving the arms to vary their relative projection from the head.

5. A machine of the kind described comprising a rotatable head, arms sliding freely on the head and projecting therefrom, a single means for moving the arms to vary their relative projection from the head, and means for locking the arms against movement.

6. A machine of the kind described comprising a pair of arms mounted to slide freely on a rotatable support, means connecting the arms so that they move at different relative speeds, tool holding devices on the arms, and means for locking the arms against movement.

7. A machine of the kind described comprising a pair of arms mounted to slide freely on a rotatable support, means connecting the arms so that they move at different relative speeds, tool holding devices on the arms, means for adjusting the devices relative to the support, and means for locking the arms against movement. 70
8. A machine of the kind described comprising a rotatable support, sliding arms projecting from the support, vertically swingable ends on the arms, and tool holding devices on said ends. 75
9. A machine of the kind described comprising a rotatable support, sliding arms projecting from the support, vertically swingable ends on the arms, a connection between the ends so that they swing in unison, and tool holding devices on said ends. 80
10. A machine of the kind described comprising a rotatable support, sliding arms projecting from the support, each arm having an end adapted to be swung vertically, tool holding devices adjustable on said ends, yielding means for holding the ends in normal position and causing them to swing in unison, and means for limiting the downward movement of said ends. 85
11. A machine of the kind described comprising a horizontally rotatable support, arms adapted to be slid horizontally so as to project from the support, means for causing said arms to slide in unison, handles on said arms to provide for their being slid, vertically swingable ends on said arms, means for limiting the downward swinging of the ends, one of said ends being longer than the other, tool holding devices on said ends, and means for adjusting said tool holding devices at various distances from the pivots of the ends. 90
12. A machine of the kind described comprising a horizontally rotatable support, arms adapted to be slid horizontally so as to project from the support, means for causing said arms to slide in unison, handles on said arms to provide for their being slid, vertically swingable ends on said arms, means for limiting the downward swinging of the ends, one of said ends being longer than the other, tool holding devices on said ends, means for adjusting said tool holding devices at various distances from the pivots of the ends, and a yielding means connecting said devices and the rotatable head to insure vertical movement of the ends in unison. 95
13. A machine of the kind described comprising a head adapted to rotate, arms adapted to slide on said head and to project therefrom, a tracer holding device on one arm, a tool holding device on the other arm, means for setting a tool in the tool holding device, means for setting said tool to limit its downward movement, and means for raising said tool in the device. 100
14. A machine of the kind described comprising a head adapted to rotate, arms adapted to slide on said head and to project therefrom, a tracer holding device on one arm, a tool holding device on the other arm, means for setting a tool in the tool holding device, means for setting said tool to limit its downward movement, means for raising said tool in the device, and means for sliding the arms on the head simultaneously, said means being adapted to be adjusted to vary the ratio of the rate of speed of the sliding movement of said arms relative to one another. 105
15. A machine of the kind described comprising a head adapted to swing, arms projecting from the head and adapted to slide therein, tool holding devices on the arms, and tools in said tool holding devices, the parts being so disposed that the operative ends of the tools and the center of the swinging movement of the head are in line. 110
16. A machine of the kind described comprising a head adapted to swing, arms projecting from the head and adapted to slide therein, tool holding devices on the arms, tools in said tool holding devices, the parts being so disposed that the operative ends of the tools and the center of the swinging movement of the head are in line, and means for sliding the arms simultaneously. 115
17. A machine of the kind described comprising a head adapted to swing, arms projecting from the head and adapted to slide therein, tool holding devices on the arms, tools in said tool holding devices, the parts being so disposed that the operative ends of the tools and the center of the swinging movement of the head are in line, and a connection between the arms for causing them to move simultaneously at different rates of speed so that the distance of their sliding movement and of their swinging movement is in the same ratio. 120
18. A machine of the kind described comprising a swinging head, parallel arms sliding in the head and projecting therefrom, a shaft in the head, pinions on the shaft and in mesh with the racks on the arms, means for supporting the arms at various heights to accommodate different size pinions on the shaft, a handle on the shaft, tool holding devices on the arms, and means for permitting a limited upward movement of the tool holding devices. 125
19. A machine of the kind described comprising a swinging head, parallel arms sliding in the head and projecting therefrom, a shaft in the head, pinions on the shaft and in mesh with the racks on the arms, means for supporting the arms at various heights to accommodate different size pinions on the shaft, a handle on the shaft, tool holding devices on the arms, the center of swinging movement of the head and of the tool hold- 130

ing devices being in line, and a spring bearing downward on the head and on the outermost of said devices and being adapted to bear upward on the innermost of said devices when the spring is raised by the outermost device.

20. A machine of the kind described comprising a head adapted to be swung horizontally, a shaft in said head, pinions on the shaft, a pair of sliding arms having racks in mesh with the pinions, a handle on the shaft, handles on the arms, means for locking the parts so that the arms can not slide, ends with a limited swinging vertical movement on the ends of the arms, tool holding devices slidably arranged on said ends, means for fastening said devices in various

positions, an operating tool in one of said devices, means for lowering the normal position of the operative tool, means for raising said tool above its normal position, a spring bearing on the head and on the outermost device and bearing under the innermost device, and means for supporting the arms at different heights to permit the use of various size pinions on the shaft, the parts being so disposed that the center of swinging movement of the head and the center of the tools are in line.

25 In testimony that I claim the foregoing 30 I have hereto set my hand this 14th day of April, 1919.

HONESTUS M. ALBEE.
